Introduction

This invention relates to a textile offset lithographing or printing method and apparatus.

The great difficulty in printing continuous webs of material from lithographic plates is that these plates are not continuous on the roller. They are thin metal strips, each end of which is attached to a groove in the roller, thus leaving a gap on the circumference of the roller. Thus, if the roller were to be continuously run in contact with the work, a space would occur between each repeat of the pattern. In printing textiles, naturally, it is desirable to obtain long rolls of fabric with the pattern repeating continuously.

The present invention has for a main object the provision of means whereby a continuous series of repeats can be applied lithographically to a textile fabric, paper or other sheet material. A further object of the invention is to provide a method of this nature in which the fabric may be printed in a number of different colours. Still further objects are to provide a relatively simple and economical method, an apparatus which is simple to construct and to operate, and a method and apparatus, which employs to a large extent existing lithographic printing mechanism.

These objects may be performed in a series of operations in which the repeat is printed with the fabric stationary, the fabric being moved forward for each repeat. Generally, the arrangement is such that printing rolls and a feeding device for the fabric are synchronized. A series of offset printing rolls, each for printing a different colour, are successively brought into contact with respective inking plates and then with the fabric. Means is provided for maintaining the synchrony of the rolls and for moving them in synchrony. Means is also provided for lifting the rolls clear of inking plates which it is not desired that they should touch and for the return run.

More specifically, according to a preferred embodiment of the invention the apparatus includes a flat bed and frame adapted to carry the entire mechanism, impression plates, a pair of parallel offset printing rollers, spaced apart and adapted to traverse the bed over which the fabric is adapted to pass into position for printing. In conjunction with the rollers, mounted on the bed frame, is a feeding and take-up mechanism for the fabric whereby the latter may be fed into position for the printing of successive repeats. The frame also includes a rack-rail running along each side, and adjacent to the rack-rail a shifting rail which can be raised or lowered for

purposes to be described. Adapted to run along the bed frame is a carriage connected to the main printing rollers which include peripheral toothed portions adapted to run along the rack-rail to rotate the rollers in synchrony, and smooth peripheral portions adapted to be engaged by the shifting rail to lift the rollers to inoperative level on the return run. The carriage also carries the usual dampening and inking arrangement. In conjunction with the fabric feeding device and the lifting rail are mechanisms operable by the movement of the carriage to initiate action of the fabric feeding mechanism, and also to trip the mechanism to move the shifting rail. Additional rails are provided on the bed for engaging the respective rollers on the positive run and for lifting them clear of the impression plates with which they are not designed to come into contact.

20 In the method carried out according to this arrangement the carriage is advanced from one end to the other on the positive run, the rollers coming into contact with their respective impression inking plates and being inked thereby 25 and avoiding contact with the other inking plates. The rollers are then successively passed over the work to complete the printing of one repeat. When this has been accomplished, the movement of the carriage trips the mechanism 30 for lifting the rollers to clear the fabric and the inking plates on the return run, and also sets in motion the mechanism for advancing the fabric for the printing of another repeat.

35 *Detailed description*

The invention will be more fully understood by reference to the accompanying drawings illustrating a particular preferred embodiment 40 and in which:

Figure 1 is a schematic diagram showing the arrangement of the apparatus in general.

Figure 2 is a fragmentary perspective view showing the apparatus of Figure 1 on a larger 45 scale, certain of the structure having been omitted for the sake of clarity.

Figure 3 is an enlarged fragmentary side elevation showing the fabric feeding mechanism in more detail.

50 Figure 4 is a further enlarged fragmentary side elevation of a portion of the mechanism shown in Figure 3.

Figure 5 is a side elevation of an alternative form of fabric feeding mechanism.

55 Figures 6 and 7 are fragmentary side views and

end elevations, respectively, of the printing rollers.

General arrangement

Referring more particularly to the drawings, the apparatus consists of a bed frame A carrying a flat bed in which there is arranged a fabric feeding mechanism B, a series of inking plates C, a carriage D carrying the printing rollers E and inking rollers F and which is adapted to reciprocate across the bed as will be well understood by one skilled in the art.

Bed frame mechanism

The bed frame A supports a pair of elongated parallel side beams 11 running the length of the apparatus and cross beams 15. Each beam 11 carries a toothed rack 17 also running the length of the apparatus. Alongside each beam 11 and mounted on the frame for slight reciprocal vertical movement is a rail 20. On the frame beneath each rail 20 and in contacting relation thereto are mounted several cams 38, each connected to an actuating bar 35. The arrangement is such that when the bar is moved from left to right of Figure 2 the cams are rotated to exert upward pressure to raise the rail 20 and when the bar is moved to the right, the upward pressure is released, allowing the rail to gravitate into a lower position at which its top edge is substantially level with the top surface of the beam 11. Brackets 38 connect the bars 35 at one end of the machine with a lever 40 pinned to the beam 11 as at 41. Movement of the lever 40 about the pin 41 will thus move the bar 35 in one direction or the other for the purposes to be described. At the other end of the machine, the bar 35 is connected by a bracket to a lever 45, pinned to the frame as at 46. There is a rail 20 and associated lever mechanism at each side of the frame A.

Mounted on each beam 11 just inside the rack are upstanding fixed rails 50 and 51, respectively. Each extends a portion of the length of the apparatus for the purpose of lifting particular printing rollers clear of impression plates, as will be explained.

Also mounted on the frame A are the impression plates C1, C2, and C3, usually made of metal, each of these plates adapted to be inked with a different colour and each to transmit this colour to one of the offset rollers. Each plate is adjustable in the bed by thumb screws 60 in a manner which will be familiar to one skilled in this art. Also mounted on the frame A is a bearing plate 65 adapted to support the fabric in position for printing. On each side of the plate 65 having parallel axes and adapted for carrying the fabric into position over the plate 65 in a manner to be described are rollers 66 and 67.

Carriage mechanism

The carriage D includes a frame work having longitudinally extending beams 70 and cross beams 73. On extensions of each end of the beams 70 are handles 75 for moving the carriage. For these may be substituted a mechanism for moving the carriage mechanically.

Extending from side to side of the carriage D and journaled in suitable bearings are the printing rollers E1, E2, and E3, each equipped with conventional offset blankets of rubber or other suitable material, held in place in a conventional manner. The bearings on which the rollers E1 and E3 are mounted are arranged for adjustment longitudinally of the frame so as to enable ad-

justment of the spacing between the offset rollers and thus to arrange for a register of the different colours. Each roller E is provided at both ends with an annular-toothed portion 91, 92 and 93 respectively, adapted at all times to engage the rack 17. Each roller E is also equipped adjacent both ends with grooves adapting the rollers to remain at bed level or to be lifted by the rails 50 and 51. The roller E3 includes a groove 103 extending the width of both the rails 50 and 51 and thus allowing the roller to be unaffected by the latter, since this roller always remains at bed level, on the positive run of the carriage, that is, towards the right of the figure. The roller E2 includes a narrower groove 102 adapted only to clear the rail 51 so that in the positive run of the carriage the roller E2 comes into contact with its printing bed, but is then lifted by the rail 50 so that it clears the bed C3. The roller E1 has no annular groove so that this roller is, on the positive run of the carriage, lifted clear of both beds C2 and C3 by the rails 50 and 51. In brief, the structure of the rollers E, and the positioning of the rails 50 and 51 adapts these rails to lift the rollers selectively, to clear the impression beds C which they are not designed to contact.

The rollers also include annular running surfaces 81, 82 and 83 adapted for contact with the shifting rail 20 when the latter is in its upper position, in which position, on the return run of the carriage, it lifts the rollers clear of all the beds. The carriage also includes the series of inking rollers F (which are shown schematically in Figure 1), as will be well understood by one skilled in the art. For the sake of clarity the inking arrangement has been omitted from Figure 2. The carriage may also, as illustrated, include small auxiliary rollers as well as the offset rollers to assist in supporting its weight, these rollers running on the bed frame.

Feeding mechanism

Used in conjunction with the feeding rollers in one form of feeding mechanism are feed and take-up drums 110 and 112 respectively, about which the fabric is adapted to travel to and from the rollers 66 and 67. These drums are mounted on parallel axes, their rotation being synchronized by a belt 117, passing about respective pulleys 115, 116. To the axis of the drum 115 is connected a toothed driving wheel 120 which is fitted with a fine ratchet 123 to prevent back-slip. The wheel 120 meshes with a worm 130 on a connecting shaft 132. On the other end of the shaft 132 is a worm 135 held in suitable bearings (not shown). With the worm 135 meshes a gear wheel 137. A belt 136 passes about another portion of the wheel 137 and also about pulleys 138 and 139 having axes in triangular relationship as indicated. The pulley 138 is mounted on a bearing block 140 which is slidably mounted, for movement longitudinally of the bed A, on a slide 142. A worm screw 143 operated by a handle 144 acts on the block 140 for moving it to right or left of the figure in the bracket, thus serving to position the pulley 138. The pulley 139 is mounted on vertically adjustable bearings 150 and is normally urged towards its downward position by a strong compression spring 152, thus constantly exerting tension on the belt 136. The belt 136 is provided with a serrated surface, which is adapted to be engaged by a peg 160 mounted on the carriage D. That is to say, the belt carries upstanding

spaced apart projections engageable by a member projecting from the carriage. In this way, movement of the carriage from left to right of the bed causes predetermined clockwise travel of the belt 136 and thus rotation of the pulley 137 and eventually of the drum 110, thereby pulling the cloth forward to the extent of movement of the belt.

Operation

The operation of the apparatus is as follows. When it is desired to print fabric with several colours the usual preparations are made in connection with each of the separate inking devices as will be well understood. The fabric is also placed in position on the feeding mechanism B with the beginning of the roll over the bed 65 and the device is ready to operate.

Positive run

The operation starts with the carriage D at the extreme left-hand end of the frame A when the fabric is in position for printing the first repeat. The carriage is moved on the positive run (from left to right of the bed as viewed in the figure). Simultaneously the inking rollers associated with the respective offset rollers E, respectively run over the plates C3, C2 and C1 respectively, thus inking these plates. Then the offset rollers E run over the plates C, respectively receiving an impression therefrom. The offset rollers E are rotated as the carriage moves, by the engagement of their respective toothed portions 91, 92 and 93 with the rack 17. Then the offset roller E3 runs over the fabric in place on the support 65, applying its impression thereto. At the same time, the rollers E2 and E1, and respective inking mechanisms are lifted clear of the plates C3 and C2 by the rails 50 and 51 as has been described. Immediately the rolls have passed over these rails, however, they are allowed to descend to bed-level and first the roller E2 and then the roller E1 contacts the fabric and passes its impression thereto. Thus three separate colours are applied in register to the fabric.

Return run

When all three rollers have passed the work and the carriage reaches the end of its positive run it comes into contact with the end of the frame and moves the levers 45. This immediately moves the bars 35 from right to left and raises the rail 20 to its upper position. In this position, the rail contacts the running surfaces 81, 82 and 83, respectively, thus lifting all the rollers E into inoperative position so that they will clear the fabric and the printing beds on the return run of the carriage. The carriage is then moved from right to left of the bed in its return run clearing the fabric and the printing beds and it eventually reaches the extreme left-hand end of the bed frame A, where it contacts the lever 40, which moves the bars 35 from left to right of the frame, allowing the rail 20 to return to its lower level and permitting all the rollers to return to contact level. At all times the toothed portions 90 engage the rack 17, thus rotating the rollers E in synchrony.

Fabric-feeding

Simultaneously with the movement of the carriage as above described, the fabric is fed forward in a manner evident from the above description of the feeding mechanism. The peg 160 engages the serrated belt 136, thus moving the fabric forward, the distance of one repeat between each

run of the carriage. On the return run, the carriage is lifted sufficiently that the peg 160 clears the belt 136. The fabric is then in position for a further printing cycle as described above.

Alternatively, the fabric may be fed in other ways, for instance by the mechanism shown in Figure 5 as follows. As the carriage D passes from left to right of the bed near the end of the printing operation a peg 200 engages a switch lever 210 making electrical contact with a switch 202, (switch not shown). This starts an electric motor 199. The motor rotates a shaft 198 on which is mounted a gear 197 engaging a toothed-wheel 196 mounted on the shaft 193. Rotation of this wheel rotates the pulley 192, thus raising the block 194 until it contacts a lever 189. Upward movement of the block 194 allows a corresponding movement of the wire 188 from which it is suspended, which in turn allows a registration control block 181 to pass back to starting position where it contacts a terminal 183. This also permits counter-revolution of the ratchet gear wheel 110 to starting position by the urge of a weight 172 operating by gravity from its suspension on a wire 170 over the pulley 171.

When the block 194 has reached the upper limit of its travel it raises the lever 189 which operates an electrical cut-off switch at 187, stopping the motor 199. This releases the block 194, which, being considerably heavier than the counterbalancing weight 172, immediately falls to the lower limit of its travel. The distance of this travel is controlled by the position of the variable stop 184 adjustable manually to various positions along the rails 182. This controls the distance of travel of the block 181. The distance between the blocks 183 and 184 is the distance through which the block 181 moves. The cloth is moved a relative amount in each cycle of operation.

As the block 194 falls it operates by means of the wires 188 and 180 and through the ratchet-gear wheel 160. The cloth-carrying drum 110 causes a definitely predetermined length of cloth to be moved over the printing bed 65 at each cycle of operation. The cloth-carrying drum is geared to the other cloth-carrying drum 112 by a shaft and bevel gearing (not shown in the drawings).

As the block 181 reaches the limit of its movement it rests against the inner face of the block 184 until the commencement of the next cycle of operation. It is held tightly in position by the gravitational pull of the block 194. This pull also holds the cloth steadily in position on the printing bed, preventing its movement during the printing operation.

This cycle of cloth-moving operations cannot be repeated until the electrical switch at 202 is reset by the resetting switch 205. The switch at 205 (switch not shown) is actuated by the carriage D on its trip back to the starting end of the machine, the peg 200 contacting and deflecting the switch lever 204. Each lever 210 and 204 is, after having performed its function, brought back into operative position by means of weights 211 and 212, respectively, attached to its lower end.

Advantages

This method and apparatus has several advantages. In the first place, the printing of a continuous textile web in several colours can be accomplished lithographically. The method and apparatus is simple and convenient. A flat bed press can be equipped according to the invention

to do continuous printing. The work accomplished is accurate and comparable with that produced by a roll printing press. Other advantages will become apparent to those skilled in the art.

It will be understood that, without departing from the spirit of the invention or the scope of the claims, various modifications may be made in the specific expedients described. The latter are illustrative only and not offered in a restricting sense, it being desired that only such limitations shall be placed thereon as may be required by the state of the prior art.

The sub-titles used throughout the specification are merely to simplify reference thereto and should otherwise be disregarded.

I claim:

1. A method of lithographically printing a fabric web in a number of different colours, comprising the steps of, applying to several non-continuous offset printing rollers aligned in a substantially horizontal plane respective impressions to appear register in a pattern, positioning a portion of a fabric web in a horizontal plane parallel to the direction of travel of said rollers, causing relative movement between said rollers and said web whereby said impressions are transferred thereto in register to print a repeat, moving said web forward to a position for printing another repeat, and again passing said rollers over the web to apply a further such repeat thereto in register with the first repeat, and so on whereby the web has applied to it a plurality of registering repeats.

2. A lithographic printing mechanism, comprising in combination, an elongated printing bed, several impression plates carried by said bed, a flat support carried by said bed for positioning a web of fabric for printing, said plates and said support being in a substantially horizontal plane, a carriage adapted to move across said bed over said plates, several printing rollers carried by said carriage and held thereby in fixed spaced apart relationship, each roller adapted to receive an impression from one of said plates, fabric feeding means associated with said fabric positioning means adapted to feed a web of fabric into position for printing, a rack on said bed and an annular toothed portion on each of said rollers adapted always to engage said rack whereby the rollers are rotated in synchrony when the carriage is moved relatively to the bed, an annular track on each roller and horizontal tracks on said bed causing each roller on the positive run of the carriage to contact its respective impression plate and to clear the other impression plates, shift means operable by the movement of said carriage causing said rollers on the return run to be lifted clear of said fabric positioning means engageable by the carriage and all said impression beds, means operable by the movement thereof to cause said feeding means to move the fabric forward to a predetermined extent between each positive run of the carriage.

3. A lithographic printing mechanism for fabric webs, comprising in combination, a bed, a plurality of impression plates mounted in series on said bed, a carriage adapted to reciprocate across said bed frame in positive and return runs, a plurality of non-continuous lithographic printing rollers connected to said carriage and adapted on the positive run of the carriage to transfer respectively different colours from the impression plates to the fabric, a fabric web support mounted in horizontal alignment with said plates,

fabric web feeding means associated with said support, means associated with said impression plates for lifting said printing rollers out of operative position as it passes over the plates corresponding to the other rollers on the positive run, a track on the bed and an annular geared portion on each roller for synchronizing the rotation of said rollers during all movements of the carriage, shift means for lifting all said printing rollers out of operative position on the return run of the carriage, means associated with said feeding means for operation by the movement of said carriage whereby the fabric web is moved forward one repeat on each movement of the carriage across the frame, means operable by the movement of said carriage for moving said shift means into lifting position on each positive run of the carriage, and means operable by the return movement of the carriage for moving said shift means into inoperative position.

4. A printing mechanism, comprising in combination, a bed frame, a plurality of impression beds mounted on said frame, each adapted to receive a different colour, a flat fabric support mounted on said frame to support a run of the fabric substantially parallel to said beds, a carriage, a plurality of non-continuous lithographic printing rollers mounted on said carriage and each adapted to receive an impression from one of said beds and to transmit it to the fabric, a rack on said frame and a geared portion on each roller for engagement therewith whereby the rollers are rotated in synchrony on movement of said carriage, a track mounted on said frame for limited vertical movement, said track running substantially the length of the frame and being adapted in operative position to engage a portion of each roller and thus to raise it from printing position, means for lifting said track, said track-lifting means being operable by movement of said carriage to move the track into operative and inoperative positions, means for feeding fabric into position on said support repeat by repeat, said feeding means being operable by movement of said carriage whereby the fabric is fed forward one repeat with each reciprocation of the carriage across the bed before the rollers come into printing contact therewith.

5. In a printing apparatus including a bed, a flat support for a portion of a web of fabric to be printed mounted on said bed, a plurality of impression plates for respectively different colours mounted on said bed in alignment with said fabric support, a plurality of non-continuous rollers adapted to pass across said plates and across the fabric and to return out of contact therewith and a frame connecting said rollers and moving therewith, feeding mechanism, a feed drum and a take-up drum for the fabric, a belt extending about pulleys and having a portion of its length parallel with the bed, belt engaging means on said carriage for engaging said belt whereby it is moved forward a predetermined distance for each run of the carriage, means for transmitting the movement of said belt to said take-up drum whereby the fabric is moved forward for each movement of the belt, and means for causing said belt engaging means to clear the belt on each return run of the carriage.

6. A printing apparatus including a support for a web of fabric to be printed, a plurality of impression plates adapted to be inked with respectively different colours, a plurality of non-continuous offset printing rolls each adapted to receive an impression from one of said plates,

operating means for moving said rollers across said plates and across the portion of fabric in printing position and to return said rolls out of contact with the fabric and plates comprising, feeding means for the fabric web, an actuating member connected to said feeding means, said actuating member being advanced by the movement of said rolls whereby the feeding means is moved with each complete movement of said rolls to advance the web one repeat.

7. A lithographic printing apparatus including a flat support for a fabric web to be printed, a plurality of impression plates mounted in the same plane as the web support and adapted to receive respectively different colours, a plurality of offset printing rollers each adapted to receive an impression from one of said plates, means for moving said printing rollers selectively into contact with said plates and with said fabric, comprising, feeding means for moving said fabric forward, a runner connected to said feeding means and adapted for moving a distance equivalent to a repeat of said pattern and returning to starting position, actuating means connected to said runner for advancing it by one repeat, means engageable by the carriage for advancing said runner, means engageable by the carriage for returning said runner to starting position, and so on.

8. A lithographic printing apparatus including a flat support for a fabric web to be printed, a plurality of impression plates in alignment with said support and adapted to receive respectively different colours, a plurality of non-continuous offset printing rollers, each adapted to receive an impression from one of said plates, means for moving said printing rollers selectively into contact with said plates and with said fabric, comprising, feeding means for moving said fabric forward, a runner connected to said feeding means, fabric-advancing means urging said runner in one direction, setting means urging the runner in the other direction, and means actuated by the movement of said printing rollers to

control the action of said advancing means and said setting means whereby said runner is moved through an advancing stroke and returned to starting position during each run of the carriage.

9. A lithographic printing mechanism, comprising in combination, a frame, several impression plates, means for positioning in substantially the same plane to said plates a web of fabric for printing, several non-continuous printing rolls each adapted to receive an impression from one of said plates and to transfer it to said web, fabric feeding means adapted to feed said web into position on said fabric positioning means for printing repeat-by-repeat, means connecting said rollers whereby they are maintained in accurately spaced-apart relationship, said frame including a rack, each of said rollers including an annular toothed portion engageable with said rack whereby the rollers are rotated in synchrony by relative movement between the rollers and the frame, the rollers being so related to the printing plates and web that relative movement therebetween on a positive run causes each roller to pick up an impression from its respective impression plate and to transfer said impression from said plate to said web, a track on said frame cooperating with an annular portion of each roller causing said roller to avoid contact with the impression plates of the other rollers, feeding means actuated by the movement between the rollers and the frame whereby the fabric is advanced a repeat after each repeat is printed and a member which in operative position increases the space between the rollers and the frame whereby the rollers clear the web and impression plates, and means operated by the relative movement between the rollers and the frame to move said member into operative position after a repeat has been printed and to move it into inoperative position prior to the printing of the next repeat.

JAMES M. LOWE.
